UNITED STATES PATENT OFFICE.

EDGAR V. SEELE, OF PHILADELPHIA, PENNSYLVANIA, ASSIGNOR TO
HOSFORD D. KELLOGG, OF PHILADELPHIA, PENNSYLVANIA.

DESIGN FOR A RADIATOR.

SPECIFICATION forming part of Design No. 36,507, dated August 18, 1903.

Application filed July 15, 1903. Serial No. 165,699. Term of patent 7 years.

To all whom it may concern:

Be it known that I, EDGAR V. SEELE, a citizen of the United States, residing in the city and county of Philadelphia, State of Pennsylvania, have invented a new, original, and ornamental Design for Radiators, reference being had to the accompanying drawing, forming part hereof, which shows the radiator in end elevation.

What I claim as new, and desire to secure to by Letters Patent, is—

The ornamental design for a radiator as shown.

EDGAR V. SEELE.
